UNITED STATES PATENT OFFICE.

MERRITT D. WILBUR, OF ROCHESTER, NEW YORK, ASSIGNOR OF ONE-HALF TO FRANCIS P. CANNON, OF SYRACUSE, NEW YORK.

CARBONIZING OR PACK-HARDENING BOX.

1,156,647.

Specification of Letters Patent.

Patented Oct. 12, 1915.

Application filed March 23, 1915. Serial No. 16,439.

To all whom it may concern:

Be it known that I, MERRITT D. WILBUR, a citizen of the United States, residing at Rochester, in the county of Monroe and State of New York, have invented a new and Improved Carbonizing or Pack-Hardening Box, of which the following is a specification.

My invention relates to boxes or pots, as they are sometimes called, in which articles of steel are packed with suitable carbonizing material for the purpose of being case-hardened, such boxes being used in connection with high temperature furnaces in the hardening rooms of manufacturing establishments.

The type of box heretofore generally used has been a plain, open top, cylindrical or rectangular receptacle of cast iron or cast steel having a cover somewhat larger than the top of the box so as to be luted thereon with fire-clay, there being no connection other than the clay between the box and the cover. It very frequently happens, however, that this clay, when subjected to the intense heat of the furnaces into which the boxes are placed, breaks off in places thus leaving cracks between the cover and box through which the carbon gases liberated from the case-hardening compound escape, and as the carbonization of the articles is due to these gases it is very essential that they be retained.

To prevent the escape of such gases, then, is the object of this invention, and I have found that by placing boxes in a furnace with their open side down, in which position the cover forms a base for supporting the box, the escape of gases will be much less as their tendency is to rise and in so doing will circulate through the box before escaping through any cracks that may be formed between the box and the base by breaking away of portions of fire-clay; and the result of this is that articles will be case-hardened to the desired depth in considerably less time than when the boxes are used with their open side up as heretofore, the furnace heat being the same of course in both instances. Therefore I have constructed a box that may be turned upside down when placed in a furnace and in which the member for closing the box becomes a base for supporting

the same above the furnace floor, such a box and modifications thereof being illustrated in the accompanying drawings, in which,

Figure 1 is a view in perspective of a box and base therefor; Fig. 2, a transverse vertical central sectional view of the box and base seen in Fig. 1; Fig. 3, a vertical sectional detail of the rear end, with respect to Fig. 1, of the box and base; Fig. 4, a plan view of a box and base of cylindrical conformation; Fig. 5, a vertical sectional view taken along the line $x-y$ of Fig. 4; Fig. 6, a top plan view of a cylindrical box of modified construction; and Fig. 7, a vertical sectional view taken along the line $x'-y'$ of Fig. 6.

Similar reference characters refer to similar parts throughout the several views.

Referring first to Figs. 1 to 3, inclusive, 1 represents a rectangular shaped cast iron or cast steel box having side and end walls 2 and 3, respectively, and a top wall 4, the bottom of the box being open. The side walls 2 have flanges 5 extending outwardly at right angles along their lower edges adapted to rest upon a base member 6 and to slidably engage in channels formed between the same and cooperating flanges 7 extending inwardly from the top edges of sides 8 on the base, such member 6 being also provided across its rear edge with an upwardly extending flange 9 against which an end wall 3 of the box will engage. The base member 6 extends forward a short distance from the front end wall 3 of the box and is provided on its under side near each corner thereof with suitable feet 10 for supporting it above the floor of a furnace; while the box is provided on its side or end walls with any suitable engaging means, as the lugs 11, whereby it may be readily handled by tongs or other devices when being placed in or removed from a furnace.

In making use of a box such as just above described, the articles to be case hardened, as indicated at 12 in Fig. 2, are packed therein with any preferred carbonizing material 13, the position of the box being with its open side uppermost. The member 6 is then slid to place on the box, as a cover, and the parts turned over so that this member 6 becomes a base for supporting the box. The box is then luted with fire-clay 14 along its sides

and ends to the base 6 and placed in a furnace, the base being supported above the floor thereof by the feet 10.

Refer now to Figs. 4 to 7, inclusive. In 5 Figs. 4 and 5 there is shown a cylindrical box 24 open at one end and having a side wall 15 and end 16. Similar and oppositely disposed circular flange sections 18 extend outwardly from the side wall 15 at the open 10 end of the box and slidably engage beneath coöperating flange sections 19 extending inwardly from circular side portions 20 formed on the periphery of the base member 21, such member being provided with suitable feet 22 preferably three in number.

The box 25, shown in Figs. 6 and 7, is quite similar to that shown in Figs. 4 and 5 but is especially constructed for receiving rings or such like articles, and, in order that 20 an unnecessary amount of carbonizing material may not be used and that there will be a like amount of such material inside and outside of the rings, the box is provided with a centrally disposed vertically extending hole 25 low cylindrical core 23. The base 26 for this box is similar to the base 21 except that a hole 27 is provided in the center thereof so that the walls of the core 23 may be subjected to the same heat as the outer wall 15. 30 It will be readily seen, also, that a rectangular box as 1 may be provided with a like core member 23. These cylindrical boxes and bases, when not luted with fire-clay 14, are turnable relatively on each other in order to 35 disengage the coöperating flanges 18 and 19 for the purpose of separating the parts. The boxes 24 and 25 are each provided with lugs 17 on their side walls 15, such lugs being similar to and for the same purpose as 40 the lugs 11 on the box 1. The walls of the boxes and bases will warp somewhat and for this reason clearance is allowed between the coöperating flanges on respective ones of these members, but the construction of the 45 boxes and bases therefor is such, as will readily be seen, that warping will be largely prevented.

It is believed that, from the foregoing description, the construction, manner of using 50 and purpose for which boxes constructed in accordance with my invention are intended are sufficiently clear to call for no further explanation herein.

What I claim is:

55 1. The combination, in a device of the character and for the purpose described, of a box having one side open, a cover slidable on and off of said box, projections formed on said cover, flanges on side walls of said box,

coöperating flanges on said cover adapted to 60 engage said first named flanges in overlapping relation, said box adapted to be placed in a furnace, bottom side up, with the cover forming a base supported above the furnace floor by said projections, and means as lugs 65 formed on said box adapted to be engaged by a suitable device therefor when placing the box in or removing it from a furnace.

2. The combination, in a device of the character and for the purpose described, of 70 a box having one side open, a cover slidable on and off of said box, flanges extending outwardly from side walls of said box, sides on said cover, and flanges extending inwardly therefrom adapted to engage said first 75 named flanges in overlapping relation.

3. The combination, in a device of the character and for the purpose described, of 80 a box member having one side open, a member for closing said open side, flanges extending outwardly from side walls of said box, sides on said closing member, flanges extending inwardly therefrom adapted to engage said first named flanges in overlapping relation, and projections formed on one 85 of said members for supporting said box above the floor of a furnace.

4. The combination, in a device of the character and for the purpose described, of 90 a box having one side open, a cover slidable on and off of said box, flanges extending outwardly from side walls of said box, sides on said cover, flanges extending inwardly therefrom adapted to engage said first named 95 flanges in overlapping relation, and projections formed on said cover, said box adapted to be placed in a furnace, bottom side up, with the cover forming a base supported above the furnace floor by said projections.

5. The combination, in a device of the character and for the purpose described, of a box 100 comprising side and bottom walls and having an open top, a cover removable therefrom and having its edges extending at all points beyond said side walls, projections formed on 105 said cover, said box adapted to be placed in a furnace, bottom side up, with said cover forming a base supported above the furnace floor by said projections, and coöperating members formed integrally with said side 110 walls and along the edges of said cover adapted to engage in overlapping relation to hold the box and cover against separation when the device is being overturned.

MERRITT D. WILBUR.
